UNITED STATES PATENT OFFICE.

JOSEPH R. BLAINE, OF CHICAGO, ILLINOIS, ASSIGNOR TO MIEHLE PRINTING PRESS & MANUFACTURING COMPANY, OF CHICAGO, ILLINOIS, A CORPORATION OF ILLINOIS.

INK DISTRIBUTION FOR PRINTING-PRESSES.

1,168,277.

Specification of Letters Patent.

Patented Jan. 18, 1916.

Application filed April 22, 1914. Serial No. 833,579.

To all whom it may concern:

Be it known that I, JOSEPH R. BLAINE, a citizen of the United States, residing at Chicago, in the county of Cook and State 5 of Illinois, have invented certain new and useful Improvements in Ink Distribution for Printing-Presses, of which the following is a specification.

The principal objects of the invention are 10 the provision of an improved system of ink distribution under which the ink is more uniformly applied to the cylinder at the points of contact therewith of the form rolls, and the mounting of the form and 15 rider rolls in such manner as to be readily brought into accessible position for cleaning, adjustment and the like.

Other advantageous features of construction and operation will be made apparent to 20 those skilled in the art from a reading of the subjoined detailed description taken in connection with the accompanying drawing upon which the description is predicated and in which, for purposes of illustration 25 only, is set forth in side elevation a preferred embodiment of the invention.

In that form of construction chosen as an example the numeral 11 designates the plate or form cylinder upon the axle 12 of which 30 is loosely mounted the collar 13 forming an integral part of a frame designated generally at 14. This frame is in the form of a segment and has suitably journaled upon its periphery a plurality of trains of rolls, 35 one train comprising the form rolls 15 and 16 and the rider rolls 17, 18 and 19, while the other train comprises form rolls 20, 21 and 22 and rider rolls 23, 24, 25, and 26. The form rolls of the two trains are driven 40 from the cylinder gear 27 at a peripheral speed corresponding to that of the cylinder by means of pinions 28, 29, 30 and 31 suitably geared to the form rolls.

In order to effect a supply of ink in 45 proper degree to both trains of rolls the final ink drum 32 of the ductor train has mounted upon its axis 33 the bearing yoke 34 of a ductor roll 35 which latter is caused in any suitable manner to oscillate upon the 50 axis of the drum with the ductor roll and ink drum in continual peripheral contact, the periphery of the ductor roll contacting alternately with the periphery of the first rider rolls 19 and 26 of each of the distributing trains respectively whereby the ink from

the drum is supplied independently to the two trains instead of indirectly to one of the trains through the other, as has been common.

In order to provide for the simultaneous 60 adjustment of the rolls of each train in their relation to the form cylinder and to throw all of the rolls simultaneously out of operative engagement with the said cylinder the frame 14 is provided with an eccentric 65 36 suitably mounted upon an axis 37 and arranged to bear upon the fixed wear block 38. The eccentric has connected thereto the lever arm 39 which in turn is connected by a link 40 with a lever 41 fulcrumed at 42. By throwing the lever 41 to the right the frame together with the trains of rolls are lifted bodily out of contact with the form cylinder and with the driving pinions out of mesh with the cylinder gear. 70 75

In order to bring the distributing train of rolls into a position readily accessible for cleaning, adjustment, or for other purposes provision is made to rotate the frame and trains of rolls bodily about the cylinder, the 80 frame being provided for this purpose with a segment rack 43 in mesh with a pinion 44 which latter is adapted to be manually rotated by any suitable means, as for instance a crank engaging the squared end 45 of its 85 shaft. By the rotating of the pinion 44 the frame and the trains of rolls will be caused to describe an arc to the right, as viewed in the drawing, so as to bring the rolls clear of the printing press frame into a position 90 of ready accessibility.

I claim:

1. In an ink distributing system, the combination with the form cylinder, of a plurality of trains of form and rider rolls arranged to apply ink to the cylinder at different points, an ink drum, means to distribute ink from the drum independently to the two trains, and means to swing the trains of rolls bodily to an accessible position for 95 cleaning or adjustment, substantially as described.

2. In an ink distributing system, the combination with the form, of a plurality of trains of form and rider rolls arranged to apply ink to the form at different points, an ink drum, a ductor roll arranged to transfer ink from the drum to the first roll of each train in turn, and means to swing the trains of rolls bodily free of the form to an access- 105 110 115

sible position for cleaning or adjustment, substantially as described.

3. In an ink distributing system, the combination with a form cylinder, of a plurality of trains of rolls each including a form roll and a rider roll, an ink drum, a ductor roll mounted to oscillate upon the drum axis in continual peripheral contact with the drum and in intermittent alternate contact with the rider roll of each train, and means to swing the trains of rolls bodily free of the form to an accessible position for cleaning or adjustment, substantially as described.

15 4. In an ink distributing system, the combination with a form cylinder, of a frame adjustable toward and from the form, a train of form and rider rolls mounted in the frame and arranged to apply ink to the cylinder, means to adjust the frame to bring the form rolls into and out of operative relation to the cylinder, and means to swing the trains of rolls bodily free of the form to an accessible position for cleaning or adjustment, substantially as described.

5. In an ink distributing system, the combination with the form cylinder, of a frame adjustable radially and concentrically thereof, a plurality of trains of form and rider rolls mounted in the frame and arranged to apply ink to the cylinder at different points, an ink drum, and a ductor roll arranged to transfer ink from the drum to the first roll of each train in turn, and means to adjust the frame radially to bring the trains of rolls into and out of operative relation to the form cylinder and concentrically about the cylinder axis to swing the frame and trains of rolls bodily to an accessible position for cleaning or adjustment, substantially as described.

45 6. In an ink distributing system, the combination with a form cylinder, of a frame adjustable radially thereof, a plurality of trains of form and rider rolls mounted in the frame and arranged to apply ink to the cylinder at different points, an ink drum forming the final member of a ductor train, and a ductor roll mounted to oscillate upon the drum axis in continual peripheral contact with the drum and in intermittent alternate contact with the first rider roll of each train, and means to adjust the frame radially to bring the trains of rolls simultaneously into and out of operative relation to the form cylinder, substantially as described.

55 7. In an ink distributing system, the combination with the form cylinder, of a frame adjustable radially thereof, a plurality of trains of form and rider rolls mounted in the frame and arranged to apply ink to the cylinder at different points, an ink drum, and a ductor roll arranged to transfer ink from the drum to the first roll

of each train in turn, an eccentric mounted on the frame and co-operating with a wear surface on the machine, a lever, and a link connecting the lever and eccentric whereby to adjust the frame radially and to bring the train of rolls into and out of operative relation to the form cylinder, substantially as described.

8. In an ink distributing system, the combination with the printing cylinder, of a pivoted frame arranged to swing about the axis of the cylinder, a train of form and rider rolls mounted in the frame and arranged to apply ink to the form, and means to swing the frame and train of rolls bodily about its pivot from an operative position to an inoperative position accessible for cleaning or adjustment.

9. In an ink distributing system, the combination with the form cylinder, of a frame, a train of form and rider rolls mounted in the frame and arranged to apply ink to the cylinder, and means to rotate the frame about the cylinder whereby to swing the frame and train of rolls to an accessible position for cleaning or adjustment, substantially as described.

10. In an ink distributing system, the combination with the form cylinder, of a frame adjustable concentrically thereof, a train of form and rider rolls mounted in the frame and arranged to apply ink to the cylinder, a segment rack on the frame, a pinion in mesh therewith, and means to rotate the pinion whereby to swing the frame and train of rolls to an accessible position for cleaning and adjustment, substantially as described.

11. In an ink distributing system, the combination with the form cylinder, of a frame adjustable concentrically thereof, a plurality of trains of form and rider rolls mounted in the frame and arranged to apply ink to the cylinder at different points, an ink drum, and a ductor roll mounted to oscillate upon the drum axis in peripheral contact with the drum and in intermittent alternate contact with the first rider roll of each train, a segment rack on the frame, a pinion in mesh therewith, and means to rotate the pinion whereby to swing the frame and trains of rolls to an accessible position for cleaning or adjustment, substantially as described.

12. In an ink distributing system, the combination with the form cylinder, of a frame adjustable radially and concentrically thereof, a plurality of trains of form and rider rolls mounted in the frame and arranged to apply ink to the cylinder at different points, an ink drum, a ductor roll mounted to oscillate upon the drum axis in continual peripheral contact with the drum and in intermittent alternate contact with the first rider roll of each train, means to adjust the frame radially to bring the trains

of rolls simultaneously into and out of operative relation to the form cylinder, and means to rotate the frame about the cylinder axis to swing the trains of rolls to an accessible position for cleaning or adjustment, substantially as described.

13. In an ink distributing system, the combination with the form cylinder, of a frame adjustable radially and concentrically therefore of, a plurality of trains of form and rider rolls mounted in the frame and arranged to apply ink to the cylinder at different points, an ink drum, a ductor roll mounted to oscillate upon the drum axis in continual peripheral contact with the drum and in intermittent alternate contact with the first rider roll of each train, means to adjust the frame radially to bring the trains of rolls simultaneously into and out of operative relation to the form cylinder, means to rotate the frame about the cylinder axis to swing the trains of rolls to an accessible position for cleaning or adjustment, the radially adjusting means comprising an eccentric mounted on the frame and coöperating with the wear surface on the machine, and a lever operatively connected with the eccentric, and the means for rotating the frame comprising a segment rack carried by the frame, a pinion in mesh therewith, and means to rotate the pinion, substantially as described.

14. In an ink distributing system, the

combination with the final ink drum of a ductor train, of a form cylinder, a plurality of trains of form and rider rolls arranged to apply ink to the cylinder at different points, and means to distribute ink from the said ink drum independently and uniformly to the two trains of form and rider rolls.

15. In an ink distributing system, the combination with the final ink drum of a ductor train, of a form cylinder, a plurality of trains of form and rider rolls arranged to apply ink to the cylinder at different points, and a ductor roll arranged to transfer ink from the said ink drum to the first rider roll of each train in turn.

16. In an ink distributing system, the combination with the final ink drum of a ductor train, of a form cylinder, a plurality of trains of form and rider rolls arranged to apply ink to the cylinder at different points, and a ductor roll mounted to oscillate about the drum axis in continual peripheral contact with said drum and in intermittent alternate contact with the first rider roll of each train.

In testimony whereof I have hereunto signed my name in the presence of two subscribing witnesses.

JOSEPH R. BLAINE.
